UNITED STATES PATENT OFFICE.

ADOLPH FRANKEL, OF NEW YORK, N. Y.

MACHINE FOR ATTACHING SNAP FASTENERS.

Application filed February 21, 1923. Serial No. 620,389.

To all whom it may concern:

Be it known that I, ADOLPH FRANKEL, a citizen of the United States, and resident of the city of New York, in the county of New 5 York and State of New York, have invented certain new and useful Improvements in Machines for Attaching Snap Fasteners, of which the following is a specification.

This invention relates to an improvement 10 in a machine for attaching snap fasteners to gloves, articles of clothing or the like, and has for its object to provide a machine of this character which will be of very simple construction, and which will, by a simple 15 stroke of a plunger, feed the snap fasteners to the proper point of attachment to the glove and secure the same thereto.

A further object of this invention is to 20 provide a machine for attaching snap fasteners in which the operation of attaching the male and female fasteners to the opposite edges of a glove or other article of clothing is performed by a single plunger stroke.

I shall hereinafter describe my improved 25 machine as adapted for use in attaching snap fasteners to gloves or the like. It will be understood, however, that without any substantial modification of its important elements of construction, the machine may be 30 readily used for the purpose of applying grommets, shoe buttons, rivets or staples or any other forms of fastening devices, without departing from the spirit of my invention.

35 I have herein described my machine in its simple form, so that its important details of construction and mode of operation may be readily understood and appreciated.

Reference is to be had to the accompanying 40 drawings, forming a part hereof, in which—

Figure 1 is a plan view of my machine;

Figure 2 is a detail sectional view showing 45 the position that the slides and fastener members are in prior to the plunger stroke which acts to fasten or secure one of the snap fastener members to a glove;

Figure 3 is a sectional view of the outer or free end of one of the slides;

50 Figure 4 is a transverse sectional view of the machine;

Figure 5 is a sectional view of a section of the glove and the male member of the snap fastener attached thereto;

55 Figure 6 is a similar view showing the female member;

Figure 7 is a sectional view of the slides which supply the parts of the female member, showing the position that they are in just prior to the movement of the plunger 60 which attaches the female member to the glove;

Figure 8 is a view, partly in section showing the clamping means for holding the glove or other article on its support which 65 holds said glove during the operation of attaching the snap fasteners;

Figure 9 is a front elevation of the machine; and

Figure 10 is a plan view of the mechanism 70 for rotating the hoppers.

Throughout the various views of the drawings, similar reference characters designate similar parts.

In the embodiment of my invention, as 75 disclosed herein, I have shown the main supporting frame of the machine of substantially rectangular form, provided with a front longitudinal frame member 1 and a rear longitudinal frame member 2. These 80 members 1 and 2 may be of any suitable length according to the size of the machine desired, and they are connected at their ends by the cross members 3 and 4. The frame thus provided may be supported upon a 85 suitable standard or a table, as may be desired.

The front member 1 is divided at a substantially central point to provide a space 90 for the operation of the plunger mechanism, work clamp and other attendant mechanism to be hereinafter described. The space just mentioned is bounded by transverse cross braces 5 and 6 which act as supports for slides 7 and 8 forming conveying means for 95 portions of snap fasteners as will be hereinafter described.

At 25 and 26 are hoppers which supply successive fastener members to the slides 7 and 8 which carry said fastener members to 100 a point below the article, such as a glove or the like, to which they are to be attached. These slides 7 and 8 constitute lower slides which are moved to a point below the glove or other article, and which carry parts of 105 one of the snap fastener members.

In Figures 5 and 6 is shown the form of snap fastener particularly adapted for use in my improved machine, wherein 11 designates the male or stud member of the fastener and 14 indicates the female or socket member which receives and interengages 110

with the stud member 11 in the usual manner.

The male member 11 is attached to an article, a portion of which is indicated at 5 76, by means of an attaching plate or disk 10 which is provided with a pair of prongs 13 adapted to extend through the fabric 76 and interengage or interlock with a flange 12 extending about the edge of the stud member 11.

In Figure 6 is shown the female or socket member of the snap fastener and the manner in which it is attached to an article, the article being indicated as at 75. The female member is shown at 14 and is provided with a pair of prongs 15 which are forced through the fabric 75 and interengage or interlock with a circumferential flange 17 which is rolled or curled on the edge of a cup-shaped 20 cover disk 16. It will be seen from the foregoing that the construction of the fastener members is such that they may be readily attached to the opposite edges of a glove, article of clothing or the like by pressure 25 together of the respective parts such as can be done by a simple plunger movement.

Mounted to slide upon the upper face of the front member 1 of the frame, is a pair of slides 18 and 19 which act to receive successive fastener members from the hoppers 30 23 and 24. As each fastener member consists of two parts or elements, two of the slides co-operate to supply the parts or elements for each fastener member. Thus, the 35 slide 8 supplies the cover disks 16 and the slide 18 supplies the female members 14.

A hopper 26 contains a plurality of stacks of disks 16 and supplies said disks one at a time to the slide 8 where said disks are received in a recess 32 provided for them, while the hopper 23, which is mounted over the slide 18, supplies successive female fastener members 14 to the slide 18 where they are received in an aperture 21 in said slide. 40 The two slides 8 and 18 thus act to carry both parts of the female member to a position above and below the article to which they are to be attached and plunger mechanism acts to unite the parts 14 and 16 together and to attach said parts in their united state to the article.

In similar manner the slides 7 and 19 co-operate to supply the parts for the male or stud member of the snap fastener. A hopper 55 24 supplies the attaching plates 10 one at a time to the slide 19 where they are successively received in an aperture 20 in said slide and a hopper 25 supplies stud members 11 one at a time to the slide 7 where they are successively received in a recess 33 provided in said slide 7 for their reception.

Each of the hoppers 23, 24, 25 and 26 is mounted upon an upright square bar 27 and said bars project downward through the 60 frame and are mounted so as to be free to

rotate therein. Mechanism is provided to enable the hoppers to be shifted about their vertical axes as will be hereinafter explained.

To permit the four slides to freely reciprocate without interference by the hoppers, each slide is provided with a central longitudinal slot through which the vertical bar or rod 27 on each hopper may project. In the slide 8 the slot just mentioned is disclosed at 31; in the slide 7 at 34; in the slide 75 18 at 29; and in the slide 19, at 30.

At 35 and 36 is disclosed a pair of supporting plates which act to support the opposite edges of the glove during the operation of securing the fastener members to it. 80 These plates 35 and 36 are located a slight distance below the under face of the slides 18 and 19 so that when the glove is resting upon the plates 35 and 36 it will not project upward in such a manner as to interfere with 85 the movement of the slides 18 and 19. A space, indicated at 68 is also provided below these plates so that the slides 7 and 8 may freely move to a position below them.

The plate 35 is provided with a central opening or aperture 37 and the plate 36 is provided with a similar aperture 38. The slide 8 is provided with a recess 32 which receives a cover disk 16 and moves it forward to a position below the aperture 37 95 in the plate 35, while the slide 18 simultaneously receives a socket member 14 in its aperture 22 and moves it forward to a position over the glove resting on the plate 35, and comes to rest directly over 100 and in alignment with the aperture 37 in said plate 35. Similarly, the slide 7 receives a stud fastener member 11 in its recess 33 and moves it forward to a position directly below the aperture 38 in the 105 plate 36, while the slide 19 receives an attaching plate 10 in its aperture 20 and moves the same over the top of the glove, whose opposite edge is resting on the plate 36, and comes to rest in direct registration or 110 alignment with the aperture 38 in said plate. The parts in this position are shown in Figures 2 and 7.

Each of the hoppers is provided with four channels or grooves 28 in which stacks of 115 their respective parts are contained, and the groove located nearest to the slide opening or recess is the groove which supplies the fastener parts to its slide. When the supply of parts in the groove 28 which is located 120 nearest to the slide opening is exhausted, the hopper is simply rotated about its vertical axis until one of the other grooves full with parts is positioned nearest to the slide opening. This is done by means of a suitable toothed rack located preferably on the under side of the machine and which is provided with a pair of toothed bars 71 and 71^a which mesh or engage with pinions or star-wheels 70 secured upon the lower ends 130

of the bars 27 upon which the hoppers are carried.

The hopper-rotating frame just described may be mounted in any way so as to slide 5 on the machine to rotate the hoppers when necessary and it may be supported in any desired manner on the frame of the machine, as by the brackets 72 which permit it to have its desired sliding movement. A 10 handle portion 73 is provided at one end of the hopper-shifting frame to permit the same to be readily shifted manually.

For the purpose of holding the glove down securely upon its supports 35 and 36 15 while the operation of attaching the fastener members to the same takes place, I provide a clamp consisting of a frame 41 having its opposite ends resting upon the plates 35 and 36 and pivoted at 42. This clamp 20 and attendant mechanism is clearly shown in Figures 1, 8 and 9, the same being omitted from Figure 4 for the purpose of avoiding complexity in that particular view.

One end of the clamping frame 41 extends 25 under the upper end of a plate 39 which is pivoted to the frame members 5 and 6 as at 40. The ends of the clamping frame which rest upon the plates 35 and 36 being preferably weighted they normally bear 30 downward upon said plates and securely hold thereon the opposite edges of the glove thrust under them. When the operation of attaching the fasteners to the glove has taken place and it is desired to release the 35 glove from the pressure of the clamp 41, this is done by pressing inwardly on a sliding arm 43 which extends through the frame member 1 and said arm is caused to exert pressure against the lower end of the plate 39 below its pivot 40, causing said plate to bear downwardly upon the end of the clamping frame which extends or projects beneath its upper end, with the result that 40 said clamping frame is moved about its pivot 42 and its ends are lifted so that the edges 45 of the glove are freed and the glove may be removed.

The clamping mechanism just mentioned provides a means for holding down the 50 opposite edges of the glove while the snap fastener members are being attached, and as a further means for holding the glove taut on its supports, I provide a finger 45 under which the central part of the wrist 55 portion of the glove is held during the snap fastener affixing operation. This finger is preferably formed as part of, or secured to a bar 44 which extends between and connects the frame members 5 and 6.

60 Pivoted at 46 to the end of the slide 13 is a link 47, which has its upper end pivoted at 48 to a frame 49. Similarly, the slide 19 is pivoted at 50 to a link 51 which has its end pivoted at 52 to the opposite side 65 member of the frame 49. The side members

of the frame extend diagonally rearward where one of them is pivoted at 55 to a link 54 having its lower end pivoted at 53 to the end of the slide 8. The other side member of the frame 49 has its rear end pivoted 70 at 58 to a link 57 which has its lower end pivoted at 56 to the end of the slide 7. It will be seen from the foregoing that as the side members of the frame 49 are connected together by a cross member 59, the four 75 slides 7, 8, 18 and 19 are connected to a single frame so that when said frame is lowered the slides are caused, by reason of their link connection to the frame, to slide towards the supporting plates 35 and 36, 80 and when the frame 49 is raised the slides are caused to move away from the plates 35 and 36 backward to the hoppers to receive snap fastener parts therefrom.

At 60 is shown a plunger which is adapted 85 to be vertically reciprocated in a boss 63 formed in the frame of the machine. This plunger 60 is provided with a portion 64 extending downward below the frame of the machine, and said portion 64 is provided 90 at its lower end with a foot-engaging plate 65. At its upper end the plunger is provided with a horizontally extending portion 62 which projects forward towards the front 95 of the machine. At the front end of this 100 horizontally extending portion 62 of the plunger, I provide a plunger member 66 having a pair of downwardly projecting punch members 67 and 69 which extend downward directly over and in line with the apertures 105 37 and 38 in the plates 35 and 36.

A spring 61 connects the plunger 60 to the cross member 59 of the slide-reciprocating frame 49 so that when said plunger is raised it will, through the medium of said 110 spring 61, raise the frame 49 so that the four slides 7, 8, 18 and 19 will be drawn back so that their apertures will move into position below the respective hoppers to receive parts therefrom.

From the foregoing the operation of my 115 improved machine will be readily understood. In the drawings, the slides are shown in a mid-way position. The normal position of the machine is attained when the plunger 60 has been raised to such an extent to cause the frame 49 to be raised so 120 that it draws the slides 7, 8, 18 and 19 towards the hoppers and positions them with their respective apertures 20, 21, 32 and 33 under their respective hoppers. Through gravity a fastener member is forced into each aperture in each slide, the aperture 20 in the slide 19 receiving a plate 10; the aperture or recess 33 in the slide 7 receiving 125 a stud member 11; the aperture 21 in the slide 18 receives a socket member 14 and the recess 32 in the slide 8 receives a cover disk 16.

Pressure on the plate 43 raises the ends 130

of the glove clamp 41 so that the edges 75 and 76 of the glove may be placed under the clamp, the central portion of the glove being held taut by the finger 45. The plunger 60 is then lowered and such lowering movement causes the slide-shifting frame 49 to be moved downwardly by reason of its connection to the plunger by the spring 61.

The downward movement of the frame 10 49 causes the slides to move simultaneously towards the glove supports 35 and 36 and such movement continues until the slides 18 and 19 are brought to rest above the opposite edges of the glove with their apertures 20 and 21 in direct alignment with the apertures 37 and 38 respectively in the supporting plates 35 and 36. Simultaneously with this the slides 7 and 8 are brought to rest below the plates 36 and 35 respectively, the parts at this time being in the position disclosed in Figures 2 and 7.

As further downward movement of the plunger 60 continues its punch members 67 and 69 pass through the respective slide apertures 21 and 20 forcing the respective snap fastener members downward through said apertures and causing their prongs 13 and 15 to pierce through the glove and interlock with the flanges 12 and 17. The 25 plunger is then permitted to ascend, such ascension drawing back the slides to their positions below their respective hoppers where they receive the next snap fastener parts in readiness for the next glove. To 30 enable a snap fastener member to be supported within the slide apertures 20 and 21 I provide the interior of each of these apertures with a pair of springs 22 which act to support the members in the openings until the members are forced past said springs 35 by the punch members 67 and 69 on the plunger.

When the supply of fastener members in the groove 28 of the hoppers, located nearest to the slide openings is exhausted the hoppers are shifted by movement of the rack until a filled groove in each hopper is located nearest to the slide openings.

The fastener members are so placed in the 50 various hoppers that they apply the snap fasteners in such a manner as is required on a glove used on the right hand. When the fasteners are to be applied to a glove used on the left hand their positions are reversed, that is, the stud fastener members 11 are used in the hopper 26 and the attaching plates 10 are carried in the hopper 23. The socket fastener members are under such circumstances carried in the hopper 24 and 55 the disks 16 for such socket members are carried in the hopper 25.

From the foregoing it is obvious that my invention is not to be restricted to the exact embodiment shown, but is broad enough to

cover all structures coming within the scope 65 of the annexed claims.

What I claim is:—

1. In a machine of the class described, the combination with an apertured article support, a pair of slides movable at an angle 70 to one another, one of said slides being adapted to carry a snap fastener member to a point below an article on the support, the other slide being adapted to carry an attaching member for said snap fastener to a 75 point above the article on the support, and plunger means for uniting the snap fastener and its attaching member together on opposite sides of an article when the same are held in registration by their respective 80 slides.

2. In a machine of the class described, the combination with an article support, means for retaining opposite edges of an article thereon, a pair of slides adapted to move below the opposite edges of said article, one of said slides being adapted to carry a male snap-fastener and the other slide being adapted to carry a cover for a female member of a snap-fastener, a pair of slides 90 adapted to move above the article when held on its support, one of said last mentioned slides being adapted to carry an attaching plate for the male snap fastener member, and the other slide being adapted to carry a female snap fastener member, and mechanism for simultaneously causing an engagement of the male fastener member with its attaching plate and the female fastener member with its cover, and uniting 95 said members to the opposite edges of the article on its support.

3. In a machine of the class described, the combination with an apertured support for an article, an apertured slide for receiving successive snap fastener members in its aperture and carrying them successively below the article placed on the support, another slide having a recess for receiving successive 105 attaching plates for the fastener members and adapted to carry them successively above the support, and means for attaching the snap fastener members to the article when one of said members is held above the article and in alignment with the aperture 110 therein and also in alignment with the attaching plate held in its slide below the aperture in the support.

4. In a machine of the class described, the combination with a pair of separated supports, each of said supports being provided with an aperture, an apertured slide movable under each of said supports, another apertured slide movable over each of said supports, and plungers adapted to extend 120 through the slides and through the supports when the apertures in the slides and in the supports are in alignment.

5. In a machine of the class described, the combination with a pair of work supports, a slide movable under each of said supports, each of said slides being provided with 6 means for retaining a portion of a snap fastener, an upper slide movable over each of said supports and above the first mentioned slides, means on said upper slides for receiving other portions of a snap 10 fastener and plunger means for causing an interengagement of the snap fastener parts while held by their respective slides.

6. In a machine of the class described, a frame, a pair of work supports thereon, 15 clamping means for holding the work on its supports, a plurality of slides, hoppers for successively supplying snap fastener parts to each of said slides, means for moving some of said slides to cause the same to 20 carry their snap-fastener parts above the work on the supports, means for moving the other slides to cause the same to carry their snap fastener parts to a position below the work on the supports and plunger mechanism 25 for uniting complementary parts of the snap fastener and attaching said fastener to the work on the supports.

7. In a machine of the class described, a plurality of slides for carrying snap- 30 fastener parts, a frame, links connecting said slides to said frame, plunger means for uniting together the snap-fastener parts carried by the slides and a connection between said frame and plunger means for 35 causing said frame to be raised and lowered simultaneously with the plunger means.

8. In a machine of the class described, the combination with a work support for holding two edges of an article, a pair of 40 lower slides movable below the opposite edges of the article held by the support, a pair of upper slides movable above the article and above the lower slides, a plurality of hoppers for holding snap-fastener parts, 45 means on each of the slides for receiving successive parts from one of said hoppers, a slide-shifting frame, links connecting the slides to the frame, plungers for uniting the parts held by the slides and securing 50 said parts to the article held on the work support and a connection between said slide-shifting frame and the plungers to cause said frame to be raised and lowered by similar movements of the plunger.

55 9. In a machine of the class described, the combination with a support for two edges of an article, hoppers for fastener members, means for receiving said fastener members successively from the hoppers and 60 carrying said members to a position adjacent to the opposite edges of the article, and plungers for simultaneously attaching a male fastener member to one edge of the

article and a female fastener member to the opposite edge. 65

10. In a machine of the class described, the combination with a support for two edges of an article, hoppers for holding parts of a male fastener and other hoppers for holding parts of a female fastener, conveyors for receiving parts of the female fastener from their hoppers and carrying said parts to a position adjacent to one edge of the article, conveyors for receiving parts of the male fastener and carrying the same 70 to a position adjacent to the opposite edge of the article, and means for simultaneously attaching said male and female fastener members to the opposite edges of said article. 75

11. In a machine of the class described, the combination with a plurality of hoppers for holding parts of a female fastener member, hoppers for holding parts of a male fastener member, slides for receiving successive fastener parts from the various hoppers, a frame, means for moving said frame, links connecting said slides to the frame whereby said slides are shifted by movement of said frame, a work support 80 upon which opposite edges of an article are supported and means for attaching male and female fastener members to the opposite edges of the article while said fastener members are held in their respective slides. 85

12. In a machine of the class described, the combination with a hopper having a plurality of grooves for receiving stacked fastener members, a central stem upon which said hopper is mounted, a slide adapted to reciprocate below said hopper, said slide having a slot through which said stem extends, an opening in said slide to receive successive fastener members from the hopper, spring supports in said opening, and means for shifting the hopper about its vertical axis to bring any one of its grooves into alignment with the opening therein whereby successive fastener members may be received into said opening from said 100 groove and brought to rest upon the springs in the opening. 105

13. In a machine of the class described, the combination with a support for opposite edges of a glove, plungers, slides, means 110 for feeding fastener members to said slides, means for causing said slides to carry the fastener members to a position adjacent the plungers whereby a single stroke of said plungers applies co-operating fastener 115 members to the opposite sides of the glove. 120

Signed at New York city, in the county of New York, and State of New York, this 19th day of February, A. D. 1923.

ADOLPH FRANKEL.
